UNITED STATES PATENT OFFICE.

CONSTANTIN JEAN TOSSIZZA, OF PARIS, FRANCE.

ELECTROMETALLURGIC TREATMENT OF ORES OF COPPER OR OTHER METALS.

SPECIFICATION forming part of Letters Patent No. 710,346, dated September 30, 1902.

Application filed August 6, 1901. Serial No. 71,104. (No specimens.)

To all whom it may concern:

Be it known that I, CONSTANTIN JEAN TOS-
SIZZA, a citizen of the Republic of France, re-
siding at Paris, France, have invented a new
5 and useful Improvement in Electrometallur-
gic Treatment of Ores of Copper, &c., of which
the following is a specification.

The direct electrolytic treatment with in-
soluble anodes of the solutions obtained by the
10 action of sulfuric acid on previously-roasted
copper ores has heretofore been impractical-
able, because it required, before all, a complete
purification of the solutions obtained in or-
der to free them of all sulfates other than the
15 sulfate of copper. Such a purification being
very difficult, the direct electrolytic treat-
ment was for that reason industrially inap-
plicable.

The present invention has for its object to
20 make possible the said electrolytic treatment
without preliminary purification.

A solution of the sulfates from treating
copper ores contains besides the sulfate of
25 copper the sulfates of other metals and in
particular the sulfate of iron. Among all
these sulfates that which is decomposed at
the lowest voltage is sulfate of copper. The-
oretically, then, by effecting the electrolysis at
30 a voltage sufficiently high to decompose the
sulfate of copper and not high enough to de-
compose the sulfates of iron and other met-
als a pure electrolytic deposit of copper ought
to be obtained; but in working with insolu-
35 ble anodes incidental phenomena of polariza-
tion do not permit the practical realization
of the indispensable theoretic condition—
to wit, the maintenance of a constant voltage
between very restricted limits. The poten-
40 tial at the poles of the electrolytic cell is not
slow to rise, and the metallic deposit, which
in the first instants of the operation was
formed of pure copper, quickly becomes im-
pure and formed almost exclusively of spongy
45 iron. It is necessary, then, in order that the
operation may be possible to be able to keep
uniform the voltage first established. This
result could be obtained by the use of soluble
metallic anodes; but in working to avoid the
50 electrolysis of the iron it would be necessary
for the said electrodes to be such as by their

solution to yield an electromotive force less
than that for the decomposition of iron. It
would be necessary, then, to use copper elec-
trodes, which would render the system im-
practicable, because there would be dissolved 55
at the anode exactly the quantity of cop-
per deposited at the cathode. Under these
conditions I have thought to use in place of
soluble electrodes insoluble anodes kept in
60 contact with sulfuric acid, and thus to util-
ize the known depolarization properties of
the said sulfuric acid. These anodes can
be made of carbon, and in this case the sul-
furic acid can be introduced outside the 65
anode or in the interior thereof, if the anode
is hollow, and it may be in the state of a so-
lution or in the gaseous state.

I have ascertained that the transforma-
tion of the sulfuric acid into sulfuric acid
at the anode gives rise to an electromotive 70
force which diminishes the necessary voltage
and lowers it to two-tenths of a volt. One
can thus obtain a very beautiful deposit of
pure electrolytic copper directly from an im-
pure solution with a sufficient intensity at a 75
voltage of about six-tenths of a volt, whereas
in all processes heretofore known one could
only obtain this electrolysis with insoluble
anodes at voltages above one and three-tenths
volts. Incidentally I may remark that the 80
copper thus obtained being tenacious and
ductile is directly laminable or it can be de-
posited directly in the form of tubes which
can be employed in industry.

It results from the preceding that sulfur-
ous acid, which has been considered an ob-
jectionable element in metallurgy and which
it has been sought to get rid of as much as
possible, becomes an auxiliary in electromet-
allurgy and makes it possible to manufacture 90
metals at voltages inferior to those of their
theoretical formation in their direct or indi-
rect electrolysis.

The sulfuric acid introduced into the elec-
trolytic bath is preferably obtained from the 95
preliminary treatment of the ores. Copper
and most metals exist in the form of sulfid
ores, which when roasted produce oxids and
sulfurous acid. The oxids are transformed
into sulfids by dissolving them in sulfuric 100

acid. The sulfurous acid is dissolved in water and the solution introduced into the electrolytic bath.

I claim—

- 5 1. The process of treating electrolytically the impure and ferruginous solutions of sulfate of copper obtainable by the solution of copper ores in sulfuric acid, in order to recover the copper electrolytically without special preparation, by proceeding with the electrolytic treatment at a voltage between about two-tenths and eight-tenths of a volt with insoluble anodes maintained in contact with sulfurous acid, substantially as described.
- 15 2. In the electrolytic decomposition of the impure solutions obtained by roasting sulfid ores and dissolving the products of such roasting, the process of recovering a metal from

said solution without preliminary treatment to remove another metal or other metals present therein, consisting in introducing sulfurous acid from the said roasting operation into the electrolytic bath, while at the same time adjusting the voltage in such manner as to effect the decomposition of the salts of the metal to be recovered and not of the other metals present in said solution, substantially as described.

In witness whereof I have hereunto signed my name in the presence of two subscribing witnesses.

CONSTANTIN JEAN TOSSIZZA.
